US00D992548S

(12) **United States Design Patent** (10) **Patent No.:** **US D992,548 S**
(45) **Date of Patent:** **** Jul. 18, 2023**

(54) **FLEXIBLE DISPLAY**

(71) Applicant: **Lenovo (Beijing) Co., Ltd.**, Beijing (CN)

CN 304974852 * 1/2019
CN 304974852 S 1/2019

(72) Inventor: **Jincherl Kwon**, Beijing (CN)

(73) Assignee: **Lenovo (Beijing) Co., Ltd.**, Beijing (CN)

(**) Term: **15 Years**

(21) Appl. No.: **29/865,185**

(22) Filed: **Jul. 13, 2022**

Related U.S. Application Data

(62) Division of application No. 29/669,603, filed on Nov. 9, 2018, now Pat. No. Des. 961,586.

(57) **CLAIM**

The ornamental design for a flexible display, as shown and described.

DESCRIPTION

FIG. 1 is a front view of a flexible display showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is a perspective view of the flexible display shown in a partially folded state; and,

FIG. 9 is a perspective view of the flexible display shown in a fully folded state.

The broken lines shown in the drawings illustrate portions of the flexible display that form no part of the claimed design.

1 Claim, 9 Drawing Sheets
